FUEL PROPORTIONING DEVICE

Donald S. Hersey, West Hartford, Conn., assignor
to United Aircraft Corporation, East Hartford,
Conn., a corporation of Delaware

Application May 10, 1940, Serial No. 334,393

13 Claims. (Cl. 123—140)

This invention relates to improvements in gas testing devices and has particular reference to an improved device for continuously testing the density of the intake air supplied to an internal combustion engine and proportioning the engine fuel supply in accordance with the engine speed and density of the intake air.

An object of the invention resides in the provision of a simplified and sensitive testing device operative to control another device, such as an engine fuel supply means, in accordance with the density of engine intake air at each engine speed.

A further object resides in the provision of means for continuously and accurately detecting the density of engine intake air at all engine speeds within the operative range.

A still further object resides in the provision of improved means for continuously sampling engine intake air and accurately detecting the density of such air at all speeds within the operative speed range of the engine and utilizing the density indication for controlling the fuel supply to the engine.

A still further object is the provision of a device for properly proportioning the fuel and air fed to an engine.

Other objects and advantages will be more particularly pointed out hereinafter or will become apparent as the description proceeds.

In the accompanying drawings in which like reference numerals are used to designate similar parts throughout, there is illustrated a suitable mechanical embodiment for the purpose of disclosing the invention. The drawings, however, are for the purpose of illustration only and are not to be taken as limiting the invention as it will be apparent to those skilled in the art that various changes in the illustrated construction may be resorted to without in any way exceeding the scope of the invention.

In the drawings,

Fig. 1 is a sectional view through an air sampling and density detecting device constructed according to the invention, and

Fig. 2 is a somewhat schematic view, partly in section, of an engine fuel supply mechanism and control therefor adapted to be operated by the density detecting apparatus illustrated in Fig. 1.

Referring to the drawings in detail, the numeral 10 generally indicates an engine intake air duct which may be some part of the aircoop 12 shown in Fig. 2, the supercharger intake 14 or the diffuser 16 on the outlet side of the supercharger, as the device will operate with equal facility on either side of the supercharger provided

it is properly adjusted for the particular location.

A variable speed variable capacity pump, generally indicated at 18, has one side thereof connected with the duct 10 by the conduit 20 and the opposite side connected with the duct through the conduits 22 and 24 and chamber 26 containing the fixed air orifice 28 provided in a diaphragm 30 extending transversely of the chamber and intercepting the airflow between the conduits 22 and 24. One side of the pump will be an intake side and the other an outlet side depending upon the direction of rotation of the pump rotor but it is not material to the operation of the device whether the chamber 26 is connected to the pump inlet or the pump outlet so long as the conduits 32 and 34 leading from the chamber upon opposite sides of the diaphragm 30 are properly connected with the indicating or control device which the density detecting apparatus is to operate.

The pump 18 includes a rotor 36 rotatable in fixed bearings in the casing 38 and driven by suitable means, such as the spur gears 40 and 42, one of which is driven from an engine drive shaft 44. The rotor carries a plurality of movable radial vanes 46 which rotate in a movable annular cage 48 provided at opposite sides with slots 50 and 52 facing the inlet and outlet apertures of the casing 38. The vanes 46 are held in contact with the inner surface of the cage by suitable means such as the loose roller 54 disposed between the inner ends of the vanes, and a casing liner 56 may be disposed between the cage 48 and the casing 38. The cage 48 may be moved by means of a reciprocable shaft 58 one end of which is connected to the cage and the other end of which is connected to a thrust bearing 60 disposed between the flyballs 62 and the speeder spring 64 of a centrifugal governor 65. The flyballs 62 may be mounted on a rotatable member 66 driven by suitable means such as the beveled gears 68 and 70 driven from the shaft 44. If desired, the governor may be adjusted by changing the loading on the speeder spring by some suitable means such as the adjustable abutment 72 and pinion 74 in a manner well known to the art. The maximum capacity of the pump may be regulated by a suitable adjustable stop for the cage 48, such as the set screw 76 which projects through the bottom of the casing 38 and contacts a lug on the cage.

With this arrangement the quantity of air passed through the pump per unit of time can be maintained substantially constant regardless of engine speed. Since the governor is driven by the engine the cage 48 will be adjusted in accord-

ance with engine speed. As the cage is moved upwardly, as viewed in Fig. 1, incident to an increase in engine speed the pump chamber below the rotor 36 will be reduced and a pump chamber will be provided above the rotor which will move the air in the opposite direction. If the cage were moved up to a position in which it was coaxial with the rotor, in which case the two pump chambers would be equal, the capacity of the pump would be reduced to zero since the air through the upper part of the rotor would move in one direction as fast as the air through the lower part moved it in the opposite direction. The adjustment is such, however, that the displacement of the pump is correctly proportioned to engine speed, over the operative speed range of the engine, so that as the speed of the pump increases its displacement per revolution will be correspondingly decreased, and vice versa. The speed and displacement of the pump are so proportioned that the total volume of air passed by the pump in a unit of time will remain substantially constant. As indicated above the displacement per revolution of the pump 18 increases with a decrease in the number of revolutions per minute. In order to place a limit on the size of the pump required a certain minimum pump speed, such as that corresponding to the normal engine idling speed, may be selected as the one to determine the size of the pump.

The air passing through the pump 18 is passed through the fixed orifice 28 in the chamber 26. Since it requires a definite pressure head to force the air through the orifice, the orifice will create a pressure differential between the two portions of the chamber 26 on opposite sides of the diaphragm 30. With air flowing through a fixed orifice at a fixed volumetric flow rate, the pressure head across the orifice is a linear function of the air density. Since the volumetric flow rate through the orifice 28 is constant over the entire operating range as described above, the pressure differential will always be directly proportional to the density of the air flowing through the orifice. Thus, the pressure difference between the two portions of the chamber 26 connected with the conduits 32 and 34 respectively will constitute an accurate indication of the density of the engine intake air and this pressure differential may be utilized for various purposes such as indicating the intake air density or controlling some apparatus in accordance with the density variations of the intake air.

Fig. 2 illustrates one manner in which the pressure difference between the conduits 32 and 34 may be utilized to control the engine fuel supply in accordance with the intake air density and may also, if desired, continuously indicate the intake air density.

In the arrangement shown in Fig. 2 a fuel nozzle 78, is operatively associated with the engine supercharger intake 14 and is connected with a variable capacity fuel pump, generally indicated at 80, by suitable conduit or channel 82, the intake side of the pump being connected by a suitable conduit 84 with a fuel source such as the gasoline tank of a vehicle.

The pump 80 may be generally similar to the pump 18 and may have a rotor 86 which is rotatable in the casing 88 and carries a plurality of radially movable vanes 90 in a movable annular cage 92, the vanes being held in operative positions by means of a loose roller 94 disposed between the inner ends of the vanes. The cage is provided with oppositely disposed slots one of

which, as indicated at 96, faces the pump outlet port and the other, as indicated at 98, faces the pump inlet port. The rotor 86 is operatively connected with an engine drive shaft and is driven at engine speed or at some fraction or multiple thereof. The movable cage 92 is connected at one side between the apertures 96 and 98 with a stem 100 which passes through a chamber 102 and is connected with the flexible diaphragms 104, 106 and 108. The diaphragm 106 extends transversely across the chamber 102 and divides this chamber into two substantially equal portions 110, connected with the conduit 32, and 112, connected with the conduit 34. The diaphragm 104 provides a flexible seal between the shaft 100 and the end of the chamber 102 containing the portion 110 and the diaphragm 108 provides a similar flexible seal between the stem 100 and the end of the chamber containing the portion 112.

With this arrangement the pressure differential created in the chamber 26 by the flow of air through the orifice 28 is transferred to the opposite end portions of the chamber 102 and acts on the transverse diaphragm 106 to move the stem 100. The stem 100 moves the cage 92 to vary the capacity of the pump 80 by varying the ratio of the pump chambers on opposite sides of the rotor 86.

Since the pump 80 is always driven at some rate in proportion to the speed of the engine, without a density correction it would always maintain a fuel supply in proportion to engine speed. With the above described density responsive apparatus, however, it will maintain a fuel supply which is proportional to engine speed and to the density of the engine intake air thereby maintaining a constant air fuel ratio for the engine or an air fuel ratio which is varied according to definite predetermined functions.

The mass of air, or weight of air per unit of time, flowing to an engine is the mathematical product of the cylinder volume of the engine multiplied by the engine speed, the density of the air at the engine intake ports and by a correction factor known as the volumetric efficiency of the engine.

The mass of fuel flowing or weight of fuel supplied to the engine per unit of time, is the mathematical product of the fuel pump volume multiplied by the fuel density and the pump speed, the pump speed being equal to engine speed times the ratio of the drive between the engine and the pump.

The mixture ratio of the fuel and air supplied to the engine is thus equal to the product of the pump volume, pump speed and fuel density divided by the product of engine cylinder volume, engine speed, intake air density and volumetric efficiency of the engine. Since the fuel density and cylinder volume are both substantially constant, the required fuel pump volume for a given fuel to air ratio becomes a function of the product of the intake air density and the volumetric efficiency of the engine cylinders. The volumetric efficiency of the engine cylinders is primarily a function of engine speed, the other factors effecting this value being of negligible importance, so that the required fuel pump volume for any given engine speed is directly proportional to the product of the density of the air at the cylinder intake ports and a factor which is a direct function of engine speed.

The fly ball governor 65, controlling the volume of the variable displacement pump 18 can be arranged to over-control or under-control the

ratio of the displacement of this pump to pump speed in a manner such that the pressure head across the orifice 28 is not directly proportional to the density of the air flowing through the orifice but instead to the product of air density and a function of engine speed, which function can be made directly proportional to the effect of the volumetric efficiency of the engine on the mass airflow at all engine speeds within a given range. If the fuel pump volume is then made directly proportional to the corrected pressure head across the orifice 28, as shown in Fig. 2, a desired fixed ratio of fuel to intake air can be maintained over the entire above mentioned range.

The indicated variation in the control of the pump 18 by the governor 65 can be accomplished in various ways such as, by interposing a cam mechanism between the flyballs 62 and the opposing spring 64 or by selecting for the spring 64 a spring having a spring rate which varies in the proper amount with compression of the spring.

If desired, a visual density indicator 114 may be connected to the conduits 32 and 34 by suitable means such as the conduits 116 and 118 to provide a continuous indication of the density of the engine intake air.

While a particular mechanical embodiment of an air density detecting apparatus and means for applying such an apparatus to control the fuel supply of an internal combustion engine have been hereinabove described and illustrated in the accompanying drawings for the purpose of disclosing the invention, it is to be understood that the invention is not limited to the particular embodiment so described and illustrated but that such changes in the size, shape and arrangement of the various parts may be resorted to as come within the scope of the subjoined claims.

Reference is made to my copending applications Serial Nos. 311,153 (filed Dec. 27, 1939), and 370,160 (filed December 14, 1940), which show and claim subject matter shown but not claimed in this application.

Having now described the invention so that others skilled in the art may clearly understand the same, what it is desired to secure by Letters Patent is as follows:

1. In an internal combustion engine operating under variable speed and load conditions, means for detecting density variations in engine intake air comprising, an engine intake air conduit, a variable displacement pump driven by said engine and means connecting both sides of said pump with said conduit, a restricted orifice in said connecting means between one side of said pump and said conduit, a pair of conduits connected respectively with the spaces at the opposite sides of said orifice for transferring the pressure differential across said orifice to an indicating or control apparatus, and means for varying the displacement of said pump in inverse proportion to the pump speed.

2. An air sampling and density detecting device for use with a variable speed motor comprising, a variable displacement pump and means connecting both sides of said pump to a fluid flow conduit, means for driving said pump by said motor at a variable speed, speed responsive means for maintaining the volumetric flow rate of said pump substantially constant, and a fixed orifice in the connecting means between one side of said pump and said conduit and means communicating with opposite sides of the orifice for measur-

ing the pressure differential and thereby the density of the fluid in the conduit.

3. A fluid sampling and density detecting device for intake air for an engine comprising, a variable displacement variable speed pump driven by the engine and means connecting both sides of said pump to an intake air conduit for continuously withdrawing air from one location in said conduit and returning the air to said conduit at a different location, a speed responsive governor also driven by the engine and varying the displacement of said pump to maintain the volumetric flow rate therethrough substantially constant, a chamber constituting a portion of the connecting means between one side of said pump and said conduit, a fixed orifice in said chamber so arranged that all of the fluid passing through said pump is constrained to pass through said orifice, and means communicating with the chamber at opposite sides of said orifice and connected to an indicating or control device.

4. An air sampling and density detecting device for intake air for an engine comprising, a variable displacement variable speed pump driven by the engine and means connecting both sides of said pump to an intake air conduit for continuously withdrawing air from one location in said conduit and returning the air to said conduit at a different location, a speed responsive governor also driven by the engine and varying the capacity of said pump to maintain the volumetric flow rate thereof substantially constant, a chamber constituting a portion of the connecting means between one side of said pump and said conduit, a partition in said chamber transverse to the airflow therethrough dividing said chamber into two parts, an orifice in said partition, and means for transmitting the pressure difference at the opposite sides of said partition to an indicating or control apparatus.

5. An air sampling and density detecting device for engine intake air comprising, a variable capacity engine driven pump connected at both sides to an intake air conduit for continuously withdrawing air from one location in said conduit and returning the air to said conduit at a different location, an engine driven speed responsive governor operatively connected with said pump to maintain the volumetric flow rate thereof substantially constant, a chamber constituting a portion of the connection between one side of said pump and said conduit, a partition in said chamber transverse to the airflow therethrough dividing said chamber into two parts, an orifice in said partition, a variable capacity fuel pump for said engine, pneumatically actuated means for regulating the capacity of said fuel pump, and means connecting the spaces in said chamber at opposite sides of said partition with said pneumatically actuated means.

6. In combination with an engine having an air intake duct and a fuel supply, means for proportioning the amount of fuel supplied to said engine to the mass of intake air flowing comprising, a variable displacement pump driven by said engine and connected at both sides to said air intake duct at spaced apart locations, an engine driven speed responsive governor operatively connected with said pump to maintain the volumetric flow rate therethrough substantially constant over a predetermined engine speed range, a chamber constituting a portion of the connection between one side of said pump and said air duct, a partition in said chamber transverse to the airflow therethrough, an orifice in said partition, a vari-

able capacity engine driven fuel pump, pneumatically actuated means for regulating the capacity of said fuel pump, and means connecting the spaces within said chamber at opposite sides of said partition with said regulating means.

7. An air sampling device for engine intake air comprising, a variable displacement engine driven pump connected at both sides to an intake air conduit for continuously withdrawing air from and returning the air to said conduit, an engine driven speed responsive governor including centrifugally actuated flyballs and a speeder spring operatively connected with said pump to maintain the volumetric flow rate through said pump substantially constant at different engine speeds, said speeder spring being designed to modify said substantially constant volumetric flow rate in accordance with the variations in the volumetric efficiency of said engine.

8. An air sampling and measuring device 20 for intake air for an engine comprising, a variable displacement pump driven by the engine and means connecting both sides of said pump to an intake air duct for continuously withdrawing air from one location in said duct and returning the 25 air to said duct at a different location, a speed responsive governor also driven by the engine and operatively connected with said pump and constructed and arranged so that it will vary the volumetric flow rate through the pump as a function of the engine volumetric efficiency, a chamber constituting a portion of the connecting means between one side of said pump and said duct, and a diaphragm in said chamber having an orifice therein, fluid pressure connections extending from said chamber, one on each side of said diaphragm, and means connected thereto for determining the pressure differential on opposite sides of the diaphragm.

9. An air sampling and measuring device for 40 engine intake air comprising, a variable displacement engine driven pump, means connecting both sides of said pump to an intake air conduit for continuously withdrawing air from one location in said conduit and returning the air to said conduit at a different location, an engine driven speed responsive governor having a speeder spring and operatively connected with said pump, said speeder spring having a variable spring rate proportioned to modify the volumetric flow rate through said pump in accordance with variations in the volumetric efficiency of said engine, a restriction in said means connecting said pump and said conduit, and means for transmitting the pressure difference at the opposite sides of said 50 restriction to an indicating or control apparatus.

10. An air sampling device for engine intake air comprising, a variable displacement engine driven pump connected at both sides to an intake air duct for continuously withdrawing air from one location in said duct and returning the air

5 to said duct at a different location, an engine driven speed responsive governor operatively connected with said pump, a chamber constituting a portion of the connection between one side of said pump and said duct, a diaphragm, having an orifice therein, in said chamber, said governor constructed and arranged to modify the volumetric flow rate of air through said orifice as a function of the volumetric efficiency of the engine, a variable capacity engine driven fuel pump, pneumatically actuated means for regulating the capacity of said fuel pump, and means pneumatically connecting the spaces within said chamber at opposite sides of said partition with said regulating means.

11. In a density responsive device connected with the air supply line of an internal combustion engine, mechanism comprising, a diaphragm having a fixed area orifice therein, variable speed adjustable displacement pump means urging a sample quantity of gas from said supply line through said orifice at a volumetric flow rate which is a function of the volumetric efficiency of the engine and means communicating with opposite sides of said diaphragm for transmitting the pressure difference on opposite sides of said diaphragm to an indicating or control apparatus.

12. In an internal combustion engine having an air intake system variable delivery means for injecting fuel into the air in said system, a conduit connected with said system downstream relative to said fuel injecting means, said conduit having a restricted passage through which the intake mixture is passed, means for maintaining a flow rate through the restricted passage such that the pressure differential across the restriction varies in accordance with changes in mixture density, and means actuated by said pressure differential for varying the delivery of said fuel injecting means to maintain the correct proportion of fuel to air for different intake air densities.

13. In a charge forming apparatus for an internal combustion engine provided with a supercharger for engine intake air, an engine driven adjustable displacement fuel pump, an air sampling device connected with the outlet of said supercharger for continuously passing a sample quantity of air from said supercharger outlet through a fixed area restriction and having means for maintaining a constant volumetric flow of said air through said restriction to provide across said restriction a pressure head proportional to the density of said intake air, and means actuated by said pressure head and operatively connected with said fuel pump for varying the quantity of fuel delivered by said pump in accordance with variations in intake air density to maintain a substantially constant proportion between the weight of intake air and the weight of fuel delivered to said engine in the same time interval.

DONALD S. HERSEY.
